VACUUM TUBE

Wilson S. Geisler, Jr., Atherton, Calif., assignor, by
mesne assignments, to Applied Radiation Corporation,
Walnut Creek, Calif., a corporation of California

Filed July 2, 1954, Ser. No. 441,087

3 Claims. (Cl. 315—3.5)

To enable the production of tubes which are, relatively speaking, "clean," that is, are evacuated to a high degree, it has been conventional practice to raise the tubes to a relatively high temperature during the evacuation cycle. However, certain inherent limitations in just how high the temperature may be raised are encountered because of the physical elements which make up the tubes. In most tubes of the type with which the present interest lies, this limitation is set by the glass elements, glass having a softening temperature of approximately 475 degrees centigrade. As a consequence, tubes which contain glass elements are normally baked out and evacuated at 450 degrees centigrade or less. This means an incomplete vacuum is obtained and the particles which remain within the vacuum envelope of the tube become ionized upon subsequent operation thereof to cause maloperation of the tube and hastening of complete tube failure. For example, it is known that failure of a cathode is most frequently the result of positive ion bombardment. As another example, the noise produced in microwave tubes is a direct result of the ions therein. While the production of noise is indeed serious in klystrons, it is yet more accentuated in other microwave tubes such as traveling wave tubes wherein the electron beam must of necessity traverse a path of considerably greater length.

Consequently, it is an object of the present invention to provide microwave tubes which are constructed of parts so that higher bakeout temperatures than those presently utilized may be applied to enable the production of more highly evacuated devices.

A feature of the invention involves the provision of a tube constructed of ceramic and metal elements which will withstand high bakeout temperatures.

A further feature involves the provision of an electron gun structure for microwave tubes of a novel ceramic and metal construction.

Yet another feature involves the provision of an improved vacuum tube construction which is inexpensive, particularly easy to assemble and, generally speaking, readily applicable to quantity production.

Other features, as well as the advantages of the present invention, will become more apparent from a perusal of the following description of the accompanying drawing wherein:

Figure 1 is a central, longitudinal, sectional view of a traveling wave tube embodying the present invention.

Figure 2 is an exploded view of the elements which make up the electron gun portion of the tube shown in Figure 1.

Figure 3 is a central sectional view of a reflex klystron embodying the present invention, and

Figure 4 is an end view of the reflex klystron.

As shown in Figure 1, the traveling wave tube generally includes an electron gun 10 adapted to produce a beam of electrons that traverse a path through a slow wave structure 11 to thereafter be collected upon a collector electrode 12 disposed at the far end of the tube. As conventionally utilized, the electrons during their traversal

2

through the slow wave structure 11 are so directed by suitable focusing coils (not shown) as to interact with a radio frequency wave that is applied to such structure in any of a number of known manners, but preferably by means of radio frequency couplers such as disclosed in my co-pending application, Serial Number 429,265, filed May 12, 1954.

In order that the desired interaction be had, the electron gun 10, the slow wave structure 11 and the collector electrode 12 are supported by a generally tubular vacuum envelope in axial alignment. In accordance with the present invention, the tube is constructed so that all of its parts which are within the vacuum envelope, as well as those which define such envelope, are composed of materials which will withstand a temperature of at least 600 degrees centigrade without deterioration of any sort. More particularly, the parts of the tube include conducting members of a metal which will not melt or be in any way adversely affected by exposure to such a temperature and insulating members, preferably of ceramic, which, unlike glass, will not soften and will not otherwise deteriorate under this elevated temperature.

The electron gun 10 is arranged in accordance with the present invention to provide for rigid and accurate

support of its internal elements and ease of external electrical connection to these elements, while at the same time, maintaining the utmost simplicity so that the gun may be readily constructed with an assembly-line type of production technique. For this purpose, the wall of

30 the electron gun defining its vacuum envelope, is of "stacked" construction; that is, a plurality of conducting members 14, 15, 16, 17, 18 that are adapted to support the cathode and other internal elements of the gun are disposed in spaced relation by a series of insulating members 20, 21, 22, 23. As best shown in Figure 2, the insulating members 20, 21, 22, 23 constitute tubular, ceramic stubs having like cross section but differing in length. Each of the element-supporting members 14, 15, 16, 17, 18 constitutes a stamping as of copper or Monel

40 that is generally of angular configuration, being stepped, as indicated for example at 15', adjacent its peripheral edge so that it may be interposed and sealed between two of the tubular, ceramic stubs in vacuum tight relation so that the vacuum envelope of the electron gun 10 is thus defined. The term "stamping," as herein used, includes parts which have been subjected to stamping, drawing, cutting and/or other die-formed operations. The radial portion of the step 15' lies between adjacent ceramic stubs with the longitudinal portions telescoping over and within

45 the two adjacent stubs respectively so as to be fixed both radially and axially of the electron gun. More centrally, the supporting members 14, 15, 16, 17, 18 have a configuration determined in accordance with the element of the electron gun 10 that they are adapted to support. 50 One of these members 14 which forms the base of the electron gun is of generally dished configuration having a central opening through which a post 24 extends, forming one terminal of a helical heater element 25. The other terminal of the heater 25 is tied, as by spot-welding, to the second of the series of annular supporting members 15. The heater 25 is supported substantially axially of

55 the electron gun 10 and is concentrically surrounded by a thermal shield 26 which is mounted on the third of the annular supporting members 16 and supports at its extremity a cathode button 27 having a suitable coating of

60 electron emitting material upon its surface. A fourth annular supporting member 17 mounts at its central portion a focusing ring 28 disposed in pre-determined annular relation adjacent the cathode button 27 and a

65 fifth supporting member 18 includes an integral annular metal disc 29 whose central opening 30 is axially aligned with the cathode and is adapted to be supplied with a

positive potential so as to constitute an anode for accelerating the electrons emitted from the described cathode button 27. A suitable getter 31 can be secured between the second and third of the annular supporting members 15 and 16.

The manner of assembly of the described gun will be, from the foregoing structural description, readily apparent. Briefly, it can involve the application of a molybdenum-manganese coating to the ends of each of the ceramic insulators 20, 21, 22, 23 which are then brought into engagement with the respective ones of the element-supporting members 14, 15, 16, 17, 18, the elements themselves having previously been secured thereon. The ceramic insulators are then secured in vacuum-sealing relation with the interposed supporting members by means of a braze, preferably of copper-gold, and an additional braze is made to seal the heater post 24 within the central opening in the disc-shaped base member 14 to thus complete the assembly of the electron gun 10.

In order to secure the electron gun 10 to the remainder of the traveling wave tube, a metallic support 32 of generally cylindrical form is secured, as by brazing, to the described anode 29. At its far end, the support 32 is rebent to form an opening adapted to closely encompass the end of a ceramic tube 33 within which the mentioned slow wave structure 11 is supported, and when so disposed, the support 32 is sealed to the ceramic tube 33 in vacuum-tight relation.

As shown in Figure 1, the slow wave structure 11 constitutes a metal helix, one end of which is spot-welded to a thin-walled metal cylinder 34 which is flanged at one end to provide a lip 35 adapted to rest against the end of the ceramic tube 33. The helix at its other end is spot-welded to a hook 36 adapted to engage the other end of the ceramic tube 33 and to be secured thereat by means of a small tubulation 37 which is spot-welded to the hook and is brazed in sealing relationship with the end of the ceramic tube 33. As shown in Figure 1, this tubulation 37 at the end of the traveling wave tube is pinched off to complete the vacuum envelope of the tube and functions during operation as the previously mentioned collector electrode 12.

Before the described tubulation 37 is pinched off, it functions as the exit during evacuation of the tube. Because of the all metal and ceramic construction of the tube, this evacuation can be carried out while the tube is maintained at a bakeout temperature of 600 degrees centigrade or more. As previously mentioned, evacuation at this elevated temperature produces a cleaner tube which will operate more effectively with, for example, a lessened noise level, and will operate furthermore in this manner for considerably greater periods of time. When the completed tube is supplied with the proper voltages and radio frequency coupling, as are well-known in the art, a reduction in the noise level of 25 percent or more and tube life of great length can be expected.

As will be apparent from the foregoing, the described construction of a traveling wave tube through utilization of a series of stacked conducting and insulating members can be employed with equal aptness to the fabrication of klystron type tubes. As shown in Figure 3, a reflex klystron embodying the present invention essentially consists of an electron gun 40 and a reflector section 41 disposed on opposite sides of a resonator cavity 42. More particularly, the electron gun 40 is arranged in a manner similar to that previously described with respect to the traveling wave tube. A heater 43 is connected between a first annular conducting member 44 forming the end of the gun and having an exhaust tubulation 45 therein, and a second annular conducting member 46 held in spaced relation with respect to the end by an annular insulating member 47, preferably of ceramic material. This second annular conducting member 46 also supports a tubular heat shield 48 which surrounds the heater 43 and mounts the dished cathode button 49

at one end thereof. Thus, it will be seen that this second annular conducting member 46 provides a common heater-cathode terminal. In addition, it provides one terminal for a suitable getter 50, the other terminal of which consists of a third annular conducting member 51 supported in spaced relation from the second conducting member 46 by a second ceramic insulator 52, such third conducting member being so formed as to mount a focusing ring 53 adapted to encompass the cathode button 49. The lengths of the ceramic insulators are individually such that sufficient insulation is provided between the various tube elements to preclude voltage breakdown at the applied D.C. potentials.

An accelerating grid 54 is held in spaced relation to the cathode button 49, being curved so as to conform to the dished configuration of its surface. The accelerating grid 54 is supported in this position on a metal cup 55 held in insulated relation with respect to the electron gun 40 by an additional ceramic insulator 56 and having a drift tube 57 formed integrally therewith centrally in its base portion so as to be axially aligned with the cathode button 49 and the accelerating grid 54. This drift tube 57 enters and is secured within a central aperture formed in the base of another metal cup 58, whose internal dimensions are such as to determine the resonant frequency of the tube in conjunction with an annular plate 59 which is inserted and brazed therein so as to form the resonator cavity 42. Suitable grids 60, 61 are secured at the end of the drift tube 57 and in the central opening in the annular plate 59 to provide the capacitive gap for the cavity 42. The reflector section 41 includes a reflector 62 supported in spaced relationship with respect to the capacitive gap on the end of a post 63 which is brazed centrally within an annular conducting member 64 formed similarly to those utilized in the fabrication of the electron gun portion of the tube and held in insulated relation from the resonator cavity 42 by an annular ceramic insulator 65 secured at the end of a metallic cup 66 brazed to the extremity of the cavity-forming cup 58, previously described.

Upon application of suitable D.C. potentials from sources (not shown) to the respective conducting members, electrons emitted from the cathode 49 will be accelerated by the described accelerating grid 54 to pass through the grids 60, 61 forming the capacitive gap and thereafter to approach the reflector 62 and be repelled for a return crossing of the gap, when in bunched relation, so as to excite oscillations within the resonator cavity 42. To provide for egress of energy from the cavity, a small opening or iris 67 is formed in one side of the cavity-forming cup 58 and is sealingly encompassed by a wave guide stub 68 which is secured in position by brazing to a relatively heavy ring 69 which closely encircles a major portion of the cavity-forming cup 58. At the end of the wave guide stub 68, a ceramic window 70 is suitably secured within a conventional wave guide flange 71.

To enable tuning of the tube, the base of the cavity-forming cup 58 is relatively thin so as to constitute, in effect, a tuning diaphragm which when flexed, varies both the cavity volume and the spacing of the grids 60, 61 that form the cavity gap. To enable variation of the diaphragm position, like flanges 72, 73 are brazed to the exterior of each of the cups 55, 66 which respectively mount the electron gun 40 and the reflector section 41 in the proper disposition relative to the resonator cavity 42. Three tuning screws 74 are adapted to adjustably join these flanges 72, 73 so that upon turning of the screws, the whole of the electron gun portion 40 of the tube will be shifted relative to the resonator cavity 42 so as to cause the previously described change in the cavity volume and gap spacing. Suitable lock nuts 75 on the tuning screws 74 enable a desired frequency to be accurately maintained. Since this reflex klystron, like the previously described traveling wave tube, is of

metal and ceramic construction, it can be baked out in the neighborhood of 600 degrees during evacuation through the described tubulation 45 at the end of the electron gun so as to produce a highly evacuated or clean tube, so as to have long life and a lower noise level than glass tubes.

Various modifications and alterations of the disclosed embodiment may be made without departing from the spirit of the invention. For example, it will be obvious that the described electron gun may be used in conjunction with traveling wave tubes or backward wave oscillators, having a slow wave structure in the form of a loaded line, rather than a helix. As a consequence, the foregoing description of one embodiment of the invention is to be considered as exemplary and not in a limiting sense and reference is made to the appended claims for indication of the actual scope of the invention.

What is claimed is:

1. In a vacuum tube, an electron gun comprising a plurality of elements adapted to act in concert to produce a pencil-like beam of electrons, said elements being radially displaced relative to the axis of said electron beam, and separate means for supporting each of said elements in spaced, insulated relation including a plurality of insulating members, and a plurality of conducting members one for each of said elements arranged in alternate stacked relation with said insulating members. 20

2. In a vacuum tube, an electron gun comprising a plurality of elements adapted to act in concert to produce a pencil-like beam of electrons, said elements being radially displaced relative to the axis of said electron beam, a plurality of annular conducting members each supporting one of said elements, and a plurality of tubu-

lar insulating members of identical cross-section interposed between said conducting members and arranged to sealingly engage and support the same in spaced relation, said conducting and insulating members forming 5 a portion of the vacuum envelope of the vacuum tube, said conducting members having like exterior dimensions but unlike interior dimensions wherefore said elements are supported in radially displaced positions.

3. A traveling wave tube comprising an evacuated envelope, an electron gun having a plurality of elements, a slow wave structure adapted to be axially traversed by a beam of electrons from said gun, a collector electrode adapted to collect the electrons after such traversal, and means including a plurality of tubular ceramic insulating members and conducting members arranged in alternate stacked relation for supporting the elements of said gun, said slow wave structure, and said collector electrode in spaced relation, and forming said evacuated envelope of said tube. 15
